UNITED STATES PATENT OFFICE.

JOSEPH F. ADAMS, OF ST. CLAIR, MICHIGAN.

BERRY-BOX.

1,130,236.

Specification of Letters Patent.

Patented Mar. 2, 1915.

Application filed June 10, 1912. Serial No. 702,782.

To all whom it may concern:

Be it known that I, JOSEPH F. ADAMS, a citizen of the United States of America, and resident of St. Clair, St. Clair county, 5 Michigan, have invented a certain new and useful Improvement in Berry-Boxes, of which the following is a specification.

My invention relates to boxes of the kind used for packing berries or other small 10 fruits or the like in shipping crates. Ordinarily, this is done by dividing the crates into two compartments, and by placing eight boxes of fruit in each compartment. Thus four boxes are placed upon four similar 15 boxes, in each compartment, and sometimes the upper boxes telescope or sink within the lower boxes.

The object of my invention is, therefore, 20 to provide a box of such character that it cannot telescope or sink within the box below.

It is also an object to provide a novel construction whereby this advantage is accomplished in a box having portions which are 25 slotted to receive the corners of the bottom, and of such construction that the slotted portions of one box each rest at an angle to the slotted portion of another box, when one box is placed upon another of the same 30 character.

To these and other useful ends my invention consists in matters hereinafter set forth and claimed.

In the accompanying drawings—Figure 1 35 is a plan of a box embodying the principles of my invention. Fig. 2 is a side elevation of said box. Fig. 3 is a plan of the bottom of the said box. Fig. 4 is an enlarged vertical section on line 4—4 in Fig. 1. Fig. 5 40 is an enlarged plan showing the positions of the corner portions of one box on top of another. Fig. 6 is a perspective of the portions shown in Fig. 5.

As thus illustrated; my invention comprises a square bottom A and a band B. The 45 said band consists of a strip of veneer scored across the grain at the points 1, 2, 3, 4, 5, 6, 7 and 8 to form the short corner portions b, the longer side walls b¹, and the still longer 50 side wall b². It will be seen that the corner portions b are provided with slots b³ that receive and hold the corners of the bottom. The ends of the band are fastened together in any suitable manner. As the sides b¹ 55 are shorter than the sides b², and as the box is practically square, it follows that the por-

tions b are not of uniform shape or angle. In other words, each portion b forms an obtuse angle with one of the sides b¹, and a much more obtuse angle with one of the 60 sides b². Consequently, when one box is given a quarter turn relative to another, and placed on top thereof, the portions b of the upper and lower boxes cross each other at an oblique angle, as shown in Figs. 5 and 65 6. This means, of course, that when this is done one box cannot telescope within the other, because when arranged in this manner one box does not fit the other. But the boxes are practically square, and can be assembled 70 in the usual manner in the shipping crate.

Broadly considered, my invention contemplates, therefore, a box having corners of non-uniform character or shape, whereby a corner of one box may rest firmly on 75 a different corner of another box, when one box is placed upon another of the same character, thus preventing the telescoping of one box within another. In addition it will be seen that the lower box is left open at the 80 corners, as at C in Fig. 6, whereby ventilation is insured for the fruit below.

With the foregoing construction, it will be seen that the corners of the box are not 85 all the same, but to the contrary are different. In other words, one corner is disposed at a certain angle, relative to the side walls of the box, and an adjacent corner is disposed at a different angle. With the construction shown, there are two corners which 90 are alike, and two corners which are different. Thus, as explained, the placing of one box upon another, with the upper box given a quarter of a turn or rotation about a vertical axis, results in leaving the corners 95 of the lower box open at the upper edges thereof. In other words, the corners of the lower box do not match or correspond to those of the upper box, under the circumstances stated. Consequently one corner 100 portion rests at an angle upon the corner portion of the lower box.

What I claim as my invention is:

1. In berry boxes, a box comprising a square bottom, and a band folded around 105 said bottom, provided with corner portions having slots for the corners of said bottom, and sections alternating with said portions to form the side walls of the box, each said portion forming an obtuse angle with one 110 section and a more acute angle with another section, whereby the said sections are

necessarily of different lengths to enable the said band to fit the said bottom, and another box of similar construction the slotted corner portions of one box being disposed at 5 an angle above those of the other box, when one box is placed upon the other, as and for the purpose set forth.

2. A box comprising a bottom and a band therefor, said band having corner portions 10 and side sections, each corner portion forming obtuse angles of different degrees with two of said sections, the sections forming the more obtuse angles being shorter than the other two sections.

3. A box comprising a bottom and a band 15 therefor, said band having corner portions and side sections, each said portion forming obtuse angles of different degrees with two of said sections, said bottom being square, and the side sections all conforming to the 20 edges of said bottom.

Signed by me at Van Buren, Crawford county, Ark., this 4th day of May, 1912.

JOSEPH F. ADAMS.
